UNITED STATES PATENT OFFICE.

JOHN M. WILBUR, OF COLORADO SPRINGS, COLORADO, ASSIGNOR OF TWO-THIRDS TO CHARLES MINIUM AND FRED B. WILBUR, OF COLORADO CITY, COLORADO.

SWITCH-OPERATING DEVICE.

SPECIFICATION forming part of Letters Patent No. 724,358, dated March 31, 1903.

Application filed May 12, 1902. Serial No. 106,899. (No model.)

To all whom it may concern:

Be it known that I, JOHN M. WILBUR, a citizen of the United States, and a resident of Colorado Springs, in the county of El Paso 5 and State of Colorado, have made certain new and useful Improvements in Switch-Operating Devices, of which the following is a specification.

My invention is an improvement in devices 10 for operating switches from a moving car, which may be a street-car, coal-car, mineral-car, or other vehicle running on the rails; and the invention consists in certain novel constructions and combinations of parts, as will 15 be hereinafter described and claimed.

In the drawings, Figure 1 is a side elevation of my invention as in use. Fig. 2 is a top plan view thereof; and Fig. 3 is a detail plan view of a switch, parts of my improved 20 apparatus being applied.

The car A, with its truck B and wheels C, and the rail D, guard-rail E, and switch-point F may be of any approved form. The switch has its point F arranged to open to the siding 25 or to close the main rail, as desired, the switch being shown closed in full lines and open in dotted lines in Fig. 3 of the drawings. The switch-operating devices may preferably be supported on the trucks, it being understood 30 that in practice I shall employ said devices at both ends of the car, so they can be operated when the car is going in either direction.

As shown, my invention includes a wheel 1, preferably edged, as shown in Fig. 3, and 35 supported on an axle 3 in a fork at the lower end of an upright shaft 2, which shaft is held at its upper end in a case 7, so it can turn and can raise and lower, as desired. It is preferred to extend the said case down, as indicated in dotted lines, as near to the bottom 40 of the shaft 2 as possible, permitting the shaft to be raised when not in use. The case 7 also affords a bearing for the short arm of the cross-lever, presently described; by which 45 the shaft 2 is raised and lowered and turned by the means presently described. Near its upper end the shaft 2 is provided with a transverse opening G, through which projects the cross-lever 4, the opening G being elongated vertically to permit any lateral movement 50 of the shaft 2 from vibration or rocking

of the car or from other cause. At its short end 4^a the cross-lever 4 operates when adjusted to either dotted-line position shown in Fig. 2 below the guides 7, arranged near the 55 upper end of the shaft 2, the said guide being so curved as to receive the short arm of the lever 4 and hold the switch-operating wheel 1 firmly down in position to operate the switch-point and prevent the said wheel from jumping out of switching connection should it strike against the side of the rail or anything else which should have a tendency to raise it. This is an important feature of my invention—that is to say, the provision 60 of means whereby the switch-operating wheel when adjusted to operating position will be held from accidental displacement until it has accomplished the adjustment of the switch-point desired. The long arm of the lever 4 65 operates within or in engagement with a guide 6, which is curved longitudinally or from front to rear to correspond with the arc described by the long arm of the lever 4 and also vertically to rock the said lever 4 up and down in 70 raising and lowering the shaft 2. The lever 4 bears beneath the guide 6 and may preferably be provided with an antifriction-roller 4^b, and the lever 4 fulcrums on the curved bearing 5, which may preferably be a journaled wheel, as shown, to relieve friction, the curvature of the bearing permitting the rocking of the lever 4 as it travels between the dotted-line positions indicated in Fig. 2.

In the operation of the described construction 85 it will be noticed that when the cross-lever 4 is in the full-line position shown in Fig. 2 it will have operated to raise the shaft 2 and the switch-setting wheel 1 to the full-line position shown in Fig. 1, wherein it will not 90 operate upon or in contact with the switch-point or rails. If now the car should approach the switch from the left-hand end of Fig. 3, the cross-lever should be adjusted to the dotted-line position H in Fig. 2, which 95 would by the one movement rock the shaft 2 to set the wheel 1 at the angle shown in full lines, Fig. 3, and lower the shaft 2 to bring the said wheel in the position to operate between the rail D and the guard-rail E, wherein 100 it will engage the free extremity of the switch-point F and throw the said switch-point to

the dotted - line position shown in Fig. 3. The reverse movement of the cross-lever 4 or the adjustment thereof to the dotted-line position I shown in Fig. 2 will lower the shaft 2 and turn it to bring the wheel 1 to the dotted-line position shown in Fig. 3, in which it would operate upon the switch-point to adjust the same from the dotted-line position indicated in Fig. 3 to the full-line position 10 shown in the same figure.

For operating the cross-lever I provide an upright shaft 10, having a crank-arm 8, connected by a pitman 9 with the cross-lever, the shaft 10 being also provided with a handle-lever 12, which may be of any suitable form and so connected with the shaft 10 that it may be extended horizontally therefrom or may be adjusted to the upright position when the switch-wheel 1 is out of operating position, 15 and a notched rack 13 may be arranged for engagement by the handle-lever to secure the same and the shaft 10 in any desired adjustment. In the adjustment of the cross-lever 4 from end to end of the curved guide 6 it 20 will be noticed it rides upon the curved bearing 5, so the end of the lever in connection with the upright shaft 2 will be caused to rise and fall, and thus raise and lower the said shaft 2 and the wheel carried thereby. 25 The switch-operating device may be carried by a base-plate J, suitably formed for connection with the truck, as shown in Fig. 1. In operation the upward and downward motions of the car will not affect the switch-operating 30 devices, as they are attached to the truck and will not be affected by the movements of the car-body.

Having thus described my invention, what I claim as new, and desire to secure by Letters 40 Patent, is—

1. The means herein described for operating switch-points, the same consisting of the upright shaft, the vertically-edgewise wheel supported at the lower end of said shaft in 45 position to engage a switch-point, said upright shaft having a transverse opening near its upper end, the cross - shaft projecting through said opening and beyond the shaft, guide devices for engagement with the extended end of the shaft, a curved fulcrum or bearing for the cross-lever, and a vertically and longitudinally curved guide for the end of the lever opposite that engaged by the upright shaft, and means for operating the 50 cross-lever, substantially as set forth.

2. The combination with the upright shaft provided at its lower end with means for operating the switch, of the vertically-rocking cross-lever connected at one end with the 55 shaft, and swinging laterally at its other end to turn the shaft, the shaft forming the center on which the lever swings laterally and means operating upon the said lever by which to rock the cross - bar vertically whereby to 60 raise and lower the shaft, substantially as set forth.

3. The combination in a switch-operating mechanism with the upright shaft and the wheel thereon for engagement with a switch-point, of a cross-lever connected with said shaft, and means whereby the said lever may be swung laterally to turn the shaft and rocked vertically to move the shaft endwise, substantially as set forth. 70

4. The combination with the shaft carrying the switch-operating wheel, of a lever connected with said shaft and projecting at both ends beyond the same, guide devices engaging one end of the lever for operating the same, and guide devices for engaging the other end of the lever, whereby to hold the shaft from upward movement when adjusted to set the switch-operating wheel into operative position, substantially as set forth. 75

5. The combination with the shaft carrying the switch-operating wheel, of the cross-lever connected with said shaft, a curved guide for the end of the lever opposite that connected with the shaft, and a curved bearing forming a fulcrum for the said cross-lever, substantially as set forth. 80

6. The combination with the shaft carrying the switch-operating wheel, of the cross-lever connected with said shaft, a curved guide engaged by the said lever, and a curved bearing 90 between the shaft and the curved guide and forming a fulcrum for the cross-lever, substantially as set forth. 95

7. In a switch-operating mechanism, the combination with the upright shaft, and the switch-operating wheel thereon, of the guide 100 curved longitudinally and vertically, the curved bearing between the guide 6 and the upright shaft, the cross-lever engaged at one end with the guide 6 and fulcruming upon 105 the curved bearing, and guides 7 for engagement with the end of the cross-lever opposite that engaged with the curved guide 6, substantially as set forth.

8. The combination of the shaft, provided 110 at its lower end with means for operating the switch, a lever connected with said shaft and projecting at both ends beyond the same, operating devices engaging one end of the lever, and devices for engaging the other end 115 of the lever, whereby to hold the shaft against upward movement when the shaft is adjusted into position to operate the switch, substantially as set forth.

9. The combination in a switch-operating 120 mechanism, of the cross-lever, a curved guide engaged by one end of said lever, the shaft carried by the other end of the lever and provided with means for operating the switch, and a curved fulcrum-bearing for the cross-lever between the shaft and the curved guide, 125 substantially as set forth.
